[57]

ABSTRACT

A photographic apparatus for automatic photography, combined with an automatic processor for receiving an exposed film strip from the photographic apparatus and processing the strip step by step through a series of treating tanks for delivery to a customer. The strip is received in a carrier slidable along a horizontal track by two lead screws extending along the track and alternately engaged with the carrier as an incident to rotation thereof between film-raised and film-lowered positions at the ends of each tank by an oscillating operator. One screw has sections of differing pitch for feeding the carrier at differing rates for differing treating intervals constituting multiples of the cycle of the operator, and the other has sections for traversing the carrier between tanks. Transfer devices at the ends of the track shift carriers between the track and an overlying return bar which is associated with a conveyor for full loop movement of carriers, several being stored on the return bar. An alternate form has a second processing track.

AUTOMATIC PROCESSOR

BACKGROUND OF THE INVENTION

This invention relates to automatic processors for moving articles step by step relative to a series of treating or processing stations for a predetermined sequence of operations and, more particularly, to an automatic processor for immersing an exposed film strip successively in different baths arranged in series, thereby to carry out the developing, washing and other steps required for the processing of a particular type of film.

While the processor is adaptable to many different processing situations, it is particularly well suited for use in a coin-operated automatic photographic apparatus of the type that typically is installed in a public place to make one or more exposures of a customer on a film strip, then to process the film strip through a series of tanks containing the requisite baths for the strip, and finally to deliver the completed photograph or photographs to the customer.

Early forms of such an apparatus are disclosed in U.S. Pat. Nos. 2,380,378 and 2,541,016, which are representative of the one basic apparatus that has met with commercial acceptance in this area for many years. Briefly, the apparatus is actuated by the insertion of an appropriate coin in a receiver to set up the proper, lighted environment in a booth or the like and, after a preselected delay permitting the subject to position himself before a camera, activates the camera to make the exposure or exposures. Then the exposed strip is delivered to a carrier to be advanced by an automatic processing mechanism past the series of processing tanks in a darkroom environment, the carrier having a film holder that is dipped in each successive tank for a preselected time interval. When the processing is completed, the strip is fed out of the cabinet of the apparatus for delivery to the customer.

It will be apparent that an automatic processor used in this manner must be reliable so as to avoid malfunctioning between the periodic servicing calls made by the vending machine personnel. Moreover, the service required should be relatively simple in view of the non-technical nature of the personnel who service the apparatus periodically to replenish the various chemical solutions, which become exhausted and to some extent contaminated by interchange of the different chemicals after prolonged periods of use.

Machines of the basic type described in the aforesaid patents have fulfilled the need with respect to black-and-white pictures for several years, and a great number of these machines are in use throughout the world. Now, however, the trade is seeking ways to provide the same type of coin-operated photographic service with color film, the processing of which is much more complex than the processing of black-and-white film. For example, substantially different time intervals are required for the different color-processing steps, and the existing machines are not readily adaptable in a commercially acceptable manner to provide substantially different intervals in a high production processor in which several film strips often may be in process simultaneously, such existing machines being relatively inflexible with respect to the timing and sequence of steps. In addition, chemical contamination is a greater problem in color processing, wherein careful control,

particularly of key chemicals, should be maintained with respect to purity and concentration as well as to temperature and treating time.

Thus, the desire for color photography in machines of the foregoing type has created a need for a new and different processor having the greater flexibility and improved performance characteristics necessary for the satisfactory processing of color film.

SUMMARY OF THE INVENTION

In keeping with the foregoing, the general object of the present invention is to provide a new and improved automatic process that is easily adaptable to virtually any desired sequence of operations and number of processing steps that might be required by a particular film strip, and specifically those steps required for color film processing wherein widely varying time intervals are used for different treating operations, and to achieve this flexibility and versatility in a commercially practical processor that is relatively simple and compact in construction, easy to service, trouble-free in operation, capable of processing several strips in close succession, and highly effective for the processing of color film or the like.

More specifically, a preferred embodiment of the processor utilizes a pair of spaced track bars along which the film carriers are slideable, with devices for transferring carriers one by one from one bar to the other and then back to the first bar for a full loop system, with a dual drive for feeding each carrier along one bar relative to each processing tank in a lowered position at a feed rate and for a time interval selected for that particular tank, independent of the intervals required for other tanks, and for traversing the carriers in a raised position between tanks, and including means for operating in timed relation with the feed drive to shift the carriers back and forth between the raised and lowered positions at appropriate times. Specific features of the invention reside in the construction and mounting of two lead screws forming the dual drive, in the ease of adapting the drive to a desired sequence, and in the simple and effective manner of agitating carriers in the liquids as an incident to the feeding of the carriers; the construction, mounting and movement of the carriers for alternate engagement with the dual drive members; the novel manner of transferring carriers between bars; and the unique operating arrangement for cooperating with the dual drive in moving the carriers from tank to tank in accordance with the selected timing, while minimizing the transfer of liquid with the film so as to prolong the effective chemical life.

The invention also resides in the novel manner of returning carriers along the second track preparatory to re-use; the construction of the processor to expedite and facilitate servicing; and the overall arrangement for maintaining positive control of each carrier at all times during the processing.

BRIEF DESCRIPTION OF THE DRAWINGS

FIG. 1 is a perspective view of the basic parts of an automatic processor embodying the novel features of the present invention, shown in combination with a photographic apparatus of the general type with which the processor may be used in a coin-operated machine.

FIG. 2 is an enlarged fragmentary perspective view taken generally from the rear side of FIG. 1 and showing different positions and carriers along the processing path, in relation to the dual drive and the operating means.

FIG. 3 is an enlarged cross-section taken substantially along the line 3—3 of FIG. 1, and showing alternate positions of the processing tanks and one of the transfer devices.

FIG. 4 is a fragmentary plan view of part of the tank arrangement as viewed from the line 4—4 of FIG. 3.

FIG. 5 is a fragmentary cross-section taken along the line 5—5 of FIG. 4.

FIG. 6 is a fragmentary cross-section taken along the line 6—6 of FIG. 4.

FIG. 7 is an enlarged fragmentary cross-sectional view taken substantially along the line 7—7 of FIG. 1 and illustrating the film-raised and film-lowered positions of a carrier and a film holder thereon.

FIG. 8 is a broken-away fragmentary side elevation of the opposite side of the film holder shown in FIG. 7.

FIG. 9 is a cross-section taken along the line 9—9 of FIG. 8.

FIG. 10 is an enlarged cross-section taken substantially along the line 10—10 of FIG. 1, with parts shown in moved positions.

FIG. 11 is a fragmentary cross-section similar to part of FIG. 10 and illustrating the beginning of a transfer of a carrier at one end of the processor, immediately before the carrier is moved to the position shown in FIG. 1.

FIG. 12 is an elevational view taken from the rear side of the processor, in the direction of the arrow 12 of FIG. 1.

FIG. 13 is a fragmentary end view from the left end in FIG. 12, as indicated by the line 13—13 thereof.

FIG. 14 is a fragmentary cross-sectional view taken substantially in horizontal plane through the dual drive members, along the line 14—14 of FIG. 13, with central portions broken away.

FIG. 15 is a plan view of the processor.

FIG. 16 is an enlarged fragmentary cross-sectional view taken substantially along the line 16—16 of FIG. 15.

FIG. 17 is a fragmentary plan view of the carrier shown in FIG. 16.

FIG. 18 is a fragmentary cross-section taken from the side of the carrier as indicated by the line 18—18 of FIG. 17.

FIG. 19 is a sectional view similar to FIG. 11 with parts in moved positions illustrating the discharge of a processed film strip.

FIG. 20 is an enlarged fragmentary cross-section taken substantially along the line 20—20 of FIG. 19.

FIG. 21 is an elevational view of parts shown fragmentarily in FIG. 20.

FIG. 22 is a fragmentary perspective view of one section of the series of tanks, shown with the tank-supporting means and a servicing cover preparatory to removal of the tank section from the processor.

FIG. 23 and FIG. 24 are fragmentary cross-sections taken substantially along the line 23—23 of FIG. 22 and illustrating different conditions of a latch for holding the cover on the tank section.

FIG. 25 is a schematic diagram of the fluid system and components thereof for operating the processor.

FIG. 26 is an enlarged longitudinal cross-sectional view of one of the control valves in FIG. 25.

FIG. 27 is a transverse cross-sectional view taken substantially along the line 27—27 of FIG. 26.

FIG. 28 is a schematic wiring diagram showing the electrical system and the basic components thereof.

FIG. 29 is a vertical cross-sectional view generally similar to FIG. 10 but illustrating one end portion of a modified form of the invention.

FIG. 30 is a view similar to FIG. 29 showing the opposite end portion of the modified form.

DETAILED DESCRIPTION OF THE FIRST EMBODIMENT

As shown in the drawings for purposes of illustration, the invention is embodied in an automatic film processor 40 for carrying an exposed film strip 41 (FIGS. 1 and 7—9) from a loading station at 42, step by step through a series of treating stations for the various steps involved in processing the film strip, and then to a discharge station at 43 for removal from the processor. As suggested previously, a primary use of such a processor is in coin-operated photographic machines of the type typically found in bus stations and other public places for exposing, developing and delivering and direct-positive film strip in a completely automatic operation and entirely in response to the insertion of a coin of a selected denomination in the machine.

An illustrative photographic apparatus is shown at 44 in FIG. 1 as including a camera having a conventional lens-and-shutter apparatus 45 positioned beside a film strip 41 that extends downwardly from a supply roll 47 through a pair of feed rolls 48 and past the lens into a guide 49 provided with additional feed rolls 50, the two sets of feed rolls being driven by selectively operable motors 51 and 52 to draw the strip off the supply roll 47 preparatory to taking the pictures, and to feed the strip through the guide 49 to the loading station 42 of the processor 40 after the pictures have been taken. A reciprocating cut-off knife 53 is operated by a motor 54 to sever the exposed lower portion 41 from the supply strip after the pictures have been taken, and a coin-actuated control mechanism, shown generally at 55, is provided to initiate and control the picture-taking operation.

Assuming that the lower end portion of the film strip is properly positioned relative to the lens, the insertion of a coin in the control mechanism 55 actuates the mechanism to initiate the automatic picture-taking sequence in a conventional manner. After a short time delay sufficient for the customer to position himself in front of the camera, the control mechanism actuates the camera through electrical lines 57 to expose the portion of the strip that is aligned with the lens, and then energizes the feed motor 51 through electrical lines 58 and 59 to drive the rolls 48 and feed the strip downwardly by a preselected increment, thereby bringing an unexposed portion of the film into alignment with the lens. Usually, the control mechanism 55 is set to make two or more exposures, with appropriate film feeding between successive exposures.

Upon completion of the full number of exposures, the cut-off motor 54 is actuated through electrical lines 60 to reciprocate the knife 53 and sever the strip above the last exposure, thereby releasing the exposed portion for delivery to the loading station 42 through the

guide 49. The feed rolls 50 are driven momentarily to discharge the severed strip through the guide while the rolls 48 are feeding a fresh portion into alignment with the lens preparatory to initiation of the next picture-taking sequence. The coin in the control mechanism 55 may be released at any appropriate time into a coin-storage box 61.

As shown generally in FIG. 1, the processor 10 is housed in an open-sided box-like frame having upright end walls 62 and 63 connected by a bottom wall 64, and includes a plurality of tanks supported in a row, herein in a straight line, on the bottom wall to form the treating stations through which each exposed film strip 41 is carried after being discharged from the photographic apparatus 44. Each tank has an open upper end through which the strips are lowered into and removed from the tank as they are moved sequentially from one tank to the next. To hold the strips, the processor includes at least one film carrier 65, and preferably several, for receiving strips one-by-one at the loading station 42, and has means supporting the carriers for movement along a path passing all of the tanks and controlling the motion of the carriers to dip each film strip successively into each of the treating tanks in moving along its path. Then, upon arrival of the carrier at the discharge station 43, the developed strip is ready for removal from the carrier for delivery to the customer.

The construction and operation of the above-described photographic apparatus 44 are well-known to those skilled in the art, and form no part of the present invention. Moreover, black-and-white film strips from this general type of apparatus have been processed automatically for many years with satisfactory results. Existing commercial machines, however, have been limited to the taking and processing of black-and-white pictures, primarily because of the state of color film technology and the complexity of the color-developing process, which requires more flexible and precise timing and careful chemical control than is required for black-and-white processing, and also requires materially different time intervals for different steps of the process. Accordingly, available automatic processors are basically unsatisfactory for the automatic processing of color film in machines of the foregoing general character.

GENERAL INTRODUCTION OF THE INVENTION

The present invention contemplates a new and improved automatic processor 10 that is easily adaptable to any sequence of operations required for the processing of color film, including materially differing time intervals in different processing stations, and in which each film strip is advanced with independent sequential control permitting the simultaneous processing of several film strips in closely spaced relation so as to accommodate successive customers without need to delay until one strip has been processed before starting the processing of another. Moreover, the processor is easily programmed for one sequence of operations, may be changed readily to vary the sequence, is relatively simple in construction and trouble-free in operation, conserves processing chemicals for longer life and more effective operation between service calls, and may be serviced in a novel

manner with less difficulty and in substantially less time than has been required with prior processors for black-and-white film. In short, the basic invention provides a highly versatile and effective processor that was designed to make color photography practical in commercial self-photography machines.

To the foregoing general ends, the basic elements of the processor 10 include a main track formed by an elongated horizontal bar 67 defining the path for the film carriers 65 past all of the processing tanks, dual drive means 68 and 69 operable to move each carrier along the bar past each of the tanks at a preselected feed rate for the particular tank, and to move the carrier between adjacent tanks at a selected traverse rate, and mechanism operable automatically at each tank to move the carrier into a film-lowered position for processing of the film through the tank at the selected feed rate, each carrier being moved automatically at the end of the selected processing interval into a film-raised position for traversing to the beginning of the next tank.

For the cyclical operation necessary in a completely automatic and repetitive process, the processor 10 also includes an elongated return track in the form of a bar 70 that is spaced from the main track 67, automatic transfer devices 71 and 72 adjacent the exit and entrance ends of the main track for removing each carrier 65 from the main track and placing it on the return track 70 at the end of a sequence and returning carriers one-by-one to the main track upon demand, as required for the processing of film strips 41 discharged by the photographic apparatus 44, and drive means for moving the carrier along the return track from adjacent the exit end of the main track to adjacent the entrance end thereof. Thus, the processor defines a full loop circuit for film carriers and advances each carrier independently and automatically through the processing portion of the circuit with a preselected sequence of timed motions to accomplish the required processing operations before returning the carrier toward its starting point preparatory to re-use.

While the present invention pertains to an automatic processor that is adaptable for use with processes involving almost any sequence of time and varying operations, and thus is particularly well suited for film processing involving a number of operations performed under carefully controlled chemical conditions with meticulous timing of each critical treatment, it is not concerned with an actual sequence of operations to be used, the actual chemicals required, or the actual time interval for any operation. Instead, the improved processor 10 is designed to be programmed simply and effectively to produce the sequence for a practical process, whatever its requirements may be, and to be adjusted easily to accommodate any later changes that may be deemed necessary as the technology changes.

With respect to the technology of color processing, it should suffice for present purposes to point out that a representative process may include immersion in one or more developers, in stop or hardening baths, as appropriate, in bleaching solutions, and in a wash or rinse after one or more of the other steps. The particular chemicals, times, washes and the like will vary with the nature of the emulsions of the particular direct-positive paper that is to be used. Herein, and for purposes of il-

lustration only, a row of ten tanks is disposed in a temperature-controlling jacket 66 along the main track 67 for a hypothetical process comprising ten different treating steps, the tanks being of different sizes selected to fit the volume requirements of the various steps of the hypothetical process. The tanks are arranged so that they substantially fill the space between the two end walls 62 and 63, each film strip 41 being immersed in the first tank at the left very close to the loading station 42 beneath the guide 49 of the photographic apparatus 44 and progressing sequentially across the frame to the last tank at the right preparatory to being delivered to the customer.

THE MAIN TRACK AND THE CARRIERS

As shown most clearly in FIGS. 1, 2 and 12, the bar 67 forming the main track is simply a smooth, cylindrical bar extending horizontally between the end walls 62 and 63 of the frame and fastened at its ends to the end walls, short coaxial sections 73 and 74 of the bar adjacent the ends being turned down to a reduced diameter for entry and exit purposes. To adapt the carriers 65 for sliding movement along the bar, each carrier has a body 75 of generally horseshoe-shaped cross-section, as viewed in a vertical plane and shown most clearly in FIGS. 2, 17 and 18. This cross-section defines a seat having a part-cylindrical wall 77 for resting on and partially encircling the track bar, and a restricted entry slot 78 extending from the underside of the body into the part-cylindrical portion. This entry slot is narrower than the diameter of the bar but wider than the reduced-diameter sections 73 and 74 so as to permit the carriers 65 to be fitted onto and removed from the bar adjacent its ends. When on the bar, the carrier bodies are freely slideable along the bar and also are rotatable about the bar.

The film carrying portion of each carrier 65 is in the form of an elongated hollow holder 79 of basically conventional form, preferably composed of sheet metal and having an open upper end for receiving a film strip 41, herein through a funnel-like inlet 80 for guiding the strip into the holder. It will be seen in FIGS. 2 and 7-9 that the holder has at least partly open sidewalls spaced to lie on opposite sides of the strip while permitting the free circulation of developing chemicals through the holder in contact with the strip. Herein, one side of the holder is formed with inclined slots 81 separated by fins 82, and the other sidewall is open except for connecting tabs 83 as shown in FIG. 8. The film strip is held primarily adjacent its longitudinal edges as shown in FIG. 9, and preferably is lightly gripped within the holder to prevent accidental displacement as the holder is immersed in a treating tank.

To support the holder 79 on the carrier body 75, an elongated arm 83 is fastened at one end to the body and projects outwardly therefrom at a preselected angle, generally radially of the track bar 67, and the holder is suspended from a pivot 84 between the outer end of the arm and the upper end of the slotted sidewall of the holder. The film-lowered and film-raised positions of a carrier are shown in FIG. 7 in full and broken lines, respectively, the holder 79 being disposed within one of the tanks when the carrier 65 is turned to the film-lowered position, and being lifted to a level well above the tanks as the carrier is turned to the film-raised posi-

tion. It will be seen that the two preferred angular positions of the carrier body producing these positions of the film holder are separated by an angle 85 (FIG. 7) of almost 90 degrees.

5 The central portion 83a of each carrier arm 83 is an upwardly offset, right-angled bend, and the inner and outer portions of the arm, joined respectively to the body 75 and to the holder 79, are coaxially aligned. This permits the arm to drop the holder substantially vertically into a tank between the two positions illustrated in FIG. 7, and provides central clearance between the arm and a rear tank wall in the position shown in dotted lines in FIG. 7. Thus, some of the tanks may extend only part way rearwardly to the rearmost portion of the row of tanks to afford greater versatility in the arrangement of tanks for optimum relative volumes of the various baths, as shown by the first and seventh tanks in FIGS. 1 and 15, the rear walls 87 and 88 of these tanks being forwardly offset partitions.

THE DUAL DRIVE

25 The dual drive means 68 and 69 for alternatively feeding and traversing each carrier 65 along the track bar 67 and two elongated lead screws which extend between the end walls 62 and 63 of the frame, parallel to the track bar 67, and are journaled at their ends in the end walls. The feed screw 68 is spaced forwardly from the track bar, that is, generally between the latter and the row of treating tanks, and the traversing screw 30 69 is behind the track bar, both screws being disposed at a level somewhat below the level of the track bar.

35 On the feed screw 68 are a plurality of axially spaced helical thread sections (see FIG. 14) of differing pitches that are engaged to advance a carrier from left to right (FIGS. 1 and 15) along the screw and the track bar 67 at rates determined by the pitch of the particular section. In this manner, the feed rates can be varied in accordance with the needs of the various processing steps to produce materially differing time intervals for different steps without regard to the axial length of the tanks. Thus, the tanks may be sized in accordance with the volume requirements of the process, so that all of 40 the chemicals will become substantially exhausted at the same time, after processing a given number of film strips, for optimum economy of operation. Where a relatively long interval is required in one tank, followed by a relatively short interval in the next tank, equal 45 volumes of chemicals being required, the tanks may be of the same width, longitudinally of the track, and threads of similar length but materially different pitches may be used to provide the different intervals. Of course, variations in tank width also may be used in 50 obtaining the desired time interval, particularly if volume requirements also are different.

55 Herein, the feed screw 68 comprises a central shaft 89 (FIG. 14) journaled at its ends in anti-friction bearings 90 in the end walls 62 and 63 of the frame, 60 with a series of tubular sleeves of selected lengths, corresponding generally to the tank widths, telescoped snugly onto the shaft between the end walls and abutting against each other in end-to-end relation, the helical flights of the screw thread sections being 65 wrapped around and soldered to the outer sides of the tubular sleeves. The section 68a at the left end of the feed screw, the upper end as viewed in FIG. 14, has an

end flange 91 formed by a washer that abuts against the frame wall 62, and has an opposite end 92 that abuts against an annular flange 93 on the next or second section 68b. Each successive section along the screw is similarly formed and mounted, so that the ends of each pair of adjacent sections are separated by an annular shoulder formed by one of the washers.

Adjacent the right end (FIG. 1) of the feed screw 68 is a snap ring 94 (FIG. 14) that is removably anchored to the screw shaft 89 and abuts against the last screw section 68n, wherein herein is a blank spacer sleeve formed without any screw flight. This end of the screw shaft extends through the bearing 90 in the end wall 63 and is rigidly attached to a gear 95 outside the wall for driving the screw. The opposite end of the screw shaft has a threaded end 97 outside the other end wall 62 with a nut 98 threaded on the shaft and tightened against the wall.

The traversing screw 69 is the same in basic construction, similar parts other than the screw sections being indicated in the drawings by the same, but primed, reference numerals. The first screw section 69a abuts against the end wall 62 and the bearing 90' therein, and the remainder of sections 69b-69n fill the space between the first section and a snap ring 95' on the screw shaft 89' adjacent the end wall 63, the last section 69n being a blank spacer. A drive gear 99 is fast on the shaft 89' outside the end wall 63 and preferably meshes on one side with the gear 95 so that the drive rates of the two lead screws are directly interrelated according to the ratio provided by the two gears. A third gear 100 also meshes with one of the drive gears to drive both screws, this gear being power-driven by a motor 101 (FIGS. 10-12 and 19) suitably mounted on the inner side of the end wall 63 with its shaft 102 projecting through the wall to the gear 100. A fan 103 on the opposite projecting end of the shaft circulates air within the frame.

With the lead screws 68 and 69 formed in the foregoing manner, the screw sections may be held on the shafts 89 and 89' entirely by the axial squeezing action of the nuts 98 and 98' which draw the shafts and the snap rings 94 and 94' toward the wall 62 to clamp the sections endwise into tight frictional engagement with each other. Accordingly, each thread section is removably telescoped onto its shaft and is readily removable therefrom for replacement in case a change in length or pitch (and therefore time interval) is deemed desirable. The result is a versatile and flexible dual drive system in which each segment of feeding and each segment of traversing may be tailored quickly and easily to the requirements of the process to be performed.

The engagement of the respective lead screws 68 and 69 with a carrier 65 to be moved along the track bar 67 is effected by two follower lugs 104 and 105 (see FIGS. 7 and 16-18) mounted on the carrier body 75 to interfit with the flights of the respective lead screws in the different angular positions of the body. Herein, the two lugs are formed on an end plate 107 fastened to one end of the body by screws 108, and are positioned so that the lug 104 projects generally forward and downward from the body toward the feed screw when the carrier is in the film-lowered or feed position, and the lug 105 projects generally rearward and downward

toward the traversing screw when the carrier is in the film-raised or traversing position. Accordingly, each lug is movable into interfitting, engaged relation with the flights of its associated screw as an incident to turning of the carrier about the track bar between the two angularly spaced positions described.

It will be seen in FIG. 7 that the follower lug 104 of each carrier 65 rests on top of the feed screw 68 as the carrier advances along the track, the projection of the lug outwardly from the carrier being greater than the radial height of the screw flights. Advantage is taken of this arrangement to agitate the film holders 79 within the tanks for effective liquid circulation and exposure of the strips to the chemicals, all in an extremely simple manner as an incident to the axial feeding of the carrier. Specifically, the shaft 89 of the feed screw 68 is eccentrically mounted in the bearings 90 to produce an up-and-down camming action by the screw sections against the feed lug during each revolution of the feed screw. This camming action is applied through the feed lug to the carrier body 75 at a point spaced outwardly from the track bar 67, and thus cooperates with gravity to raise and lower the film holders continuously with a gentle, agitating motion that is effective to maintain motion between the film strip and the treating liquids.

At the trailing end of each screw thread section on the feed screw 68 is a gap 109 (see FIG. 14) in the thread, separated from the next thread section by one of the shoulders 93 which, in effect, form stops for holding the feed lug 104 in a dwell position at the end of each feed section preparatory to rotation of the carrier 65 to the film-raised position for traversing the next tank. The leading end portion of each thread section of the traversing screw 69 is axially aligned with or overlaps the dwell gap 109 in a feed section so as to receive the traversing lug 105 and initiate traversing of the carrier during such rotation. Similarly, the trailing end portion of each traversing screw section axially overlaps the leading end of the next feed section so as to move the carrier and the lug into alignment with the feed section before the carrier is rotated back to the feed position, and has a gap 109' for a dwell of the traversing lug adjacent a stop shoulder 93'.

THE OPERATOR FOR ROTATING THE CARRIERS

Turning or rotation of the carriers 65 between the two angularly spaced positions at the beginning and end of each timed interval is accomplished by mechanism including an operator 110 mounted on the frame for periodic movement between a raised, pick-up position and a lowered, traversing position, and engageable with a coupling abutment 111 on each carrier dwelling at the end of a feed section to shift the carrier from the film-lowered position to the film-raised position, thereby to terminate treating in one tank and initiate traversing of the carrier to the next tank. Moreover, the operator herein holds the carrier in the film-raised position during traversing, and returns it to the film-lowered position after the carrier has been moved into alignment with the next tank.

In this instance, the coupling abutment 111 on each carrier 65 is an upwardly facing surface on a plunger 112 (see FIG. 16) projecting rearwardly from the rear side of the carrier body 75, the plunger comprising a generally cylindrical sleeve telescoped over a rearward

extension 83b of the carrier arm 83 and secured thereto with a lost-motion connection formed by a pin 113 extending through alined holes in the sleeve and an elongated slot in the arm extension. A spring 114 is coiled around the arm extension 83b and compressed to urge the plunger rearward until the pin abuts against the rear end of the slot, thus holding the plunger yieldably in an extended position. The pin also prevents the plunger from turning about the extension and thereby holds the abutment surface 111 in an upwardly facing position, the rear end of the plunger sleeve being beveled at 115, downwardly and forwardly to form a cam surface on the plunger.

The operator 110 comprises an elongated operating bar 117 (see FIGS. 2, 12 and 14) parallel to the track bar 67 and of approximately the same length, means at the ends of the bar supporting the latter for up and down movement behind the track bar, preferably along an arc concentric with the track bar, and a series of operating abutments 118 spaced apart along the operating bar for engagement with the coupling abutments 111 of the carriers at appropriate points along the track. The ends of the operating bar are fastened, as by welding, to the free ends of two parallel arms 119 each telescoped loosely at its other end over an enlargement on the end of the track bar so as to pivot in unison about the axis of the track bar. The length of the arms is such that the operating abutments 118 are spaced the same distance from the axis of the track bar as are the coupling abutments 111 on the carriers 65 moving along the track bar, and thus swing along the same arc about the bar.

As shown most clearly in FIGS. 2, 12 and 14, the operating abutments herein are downwardly facing, axially elongated shoulders on split sleeves 120 telescoped on the operating bar 117 and clamped adjustably in spaced positions thereon by means of screws connecting flanges on the two halves of each sleeve. When the clamping screws are loosened, the split sleeves may be slid to any selected longitudinal positions, according to the spacing of the thread sections on the transversing screw 69, and then fixed in place, both angularly and longitudinally, by tightening the clamping screws. One abutment is provided for each transition from one tank to another.

To move the operating bar 117 up and down, a reciprocating actuator 121 (FIGS. 7, 12 and 25) is attached to the bar and operated on a timed basis providing a selected minimum treating cycle constituting one cycle of the operator, with longer treating cycles in multiples of the minimum cycle. Herein, the actuator is a fluid-powered cylinder disposed in an upright position with its lower end pivoted between two L-shaped brackets 122 on the bottom wall of the frame and with a piston rod 123 projecting upwardly out of its upper end to a pivot 124 approximately midway between the ends of the operating bar. The bar is disposed below the level of the two lead screws 68 and 69 in its lowered position and is almost directly above the traversing screw 69 in its raised position. These extreme positions are determined by stop plates 125 and 127 (see FIGS. 3, 10 and 11) on each of end walls 62 and 63 engageable with the arms 119 of the operator. A spring 128 is stretched between the operating bar 117 and the upper portion of the frame to assist the cylinder in raising the bar.

The cylinder 121 is of the double-acting type and is controlled by a valve 129 (see FIGS. 3 and 25) through which fluid under pressure is admitted alternately to lines 130 and 131 leading to the opposite end portions 5 of the cylinder. The condition of the valve is controlled by a solenoid 132 which is actuated by two timing motors 133 and 134 (FIGS. 12 and 28) to provide the minimum dwell of the operator 110 in the raised position, for example, for a period on the order of two 10 seconds, followed by a downstroke, a dwell in the lowered position for any selected interval sufficient for traversing, such as one second, and an upstroke to return the operator to the raised position. The timing motors control the dwell interval of the operator 110 in the raised position by maintaining the solenoid 132 deenergized with the valve 129 in the condition shown in full lines in FIG. 26 in which a pressure line 135 communicates with the line 130 leading to the lower end of 15 the cylinder 121 to maintain the piston rod 123 extended. After the timed interval, the solenoid is energized to shift the spool 137 of the valve to the right to the broken-line position in which the pressure line 135 communicates with the line 131 leading to the upper 20 end of the cylinder, thus retracting the piston rod to lower the operator 117. The selected interval for the lowered position is then timed before the solenoid is deenergized to return the valve spool to its full line 25 position and thereby extend the piston rod and raise the operator.

Each operating abutment 118 is positioned along the operating bar 117 to engage the coupling abutment 111 on a plunger 112 of a carrier 65 dwelling on the track bar 67 at the end of a section of the feed screw 68 during a downstroke of the operator 110, thereby to swing the plunger down with the operator while turning the carrier about the track bar to the film-raised position, raising the film holder 79 out the tank wherein the treatment has been completed. It will be seen that this raising motion of each film holder is in a vertical plane and is free of any movement longitudinally of the track. This maintains the film holder momentarily above each tank from which it has been withdrawn so that the liquid from the tank has time to drain off the holder and the film strip 41 therein, and to fall back into the tank, thereby reducing the amount of such liquid that is carried to the next tank as contamination.

To control the movement of the film holders 79 as 35 they are lifted out of the tanks during the downstrokes of the operator 110, the rate of flow of exhaust fluid out of the lower end of the cylinder 121 through the line 130 and the valve 129 is controlled, as shown in FIGS. 26 and 27, by a restriction 138 formed by a manually 40 adjustable needle valve 139 partially closing a bleed passage 140, and also by a regulating plunger 141 positioned by the operator 117 and controlling the escape of fluid through a second bleed passage 142. Both of 45 these bleed passages open into the valve bore 143 adjacent the solenoid 132 so as to receive exhaust fluid from the line 130 when the spool 137 is in the dotted-line position to deliver air from the pressure line 135 to the line 131 leading to the upper end. Thus, the combined flow areas of these two bleed passages control 50 the rate of downward movement of the operator 110 and the accompanying upward movement of the film holders 79.

It will be seen in FIG. 27 that the plunger 141 is urged upwardly by a spring 144 coiled around its upper end portion and compressed between the valve body and a head 145 on the plunger. A snap ring 147 adjacent the lower end limits upward motion to hold the plunger normally in an upwardly extended position in which an annular groove 148 in the plunger is alined with the bleed passage 142. The head 145 of the plunger is positioned to be engaged by the operating bar 117 as the latter is lowered (see FIG. 3), herein when the bar is just over half-way through its downstroke. Accordingly, the operating bar then pushes the plunger down to shift the groove 148 out of the bleed passage 142, thereby reducing the exhaust flow area to the area selected by adjustment of the needle 139, plus an insignificant amount of leakage past the plunger. Finally, when the plunger is almost fully depressed, the first one of a series of grooves 149 (FIG. 27) on the upper portion becomes alined with the bleed passage to restore the approximate, original bleed rate while the grooves are moving through the passage, until the operator completes its downstroke.

As a result, the operator 110 begins its downstroke at a relatively rapid state which continues until the groove 148 is shifted out of the bleed passage 142. Then the rate is reduced substantially near the end of the stroke, to a slow rate that is set by the needle valve 139 for a momentary pause, and the operator finally completes its stroke with a short, rapid motion that snaps the arms 119 sharply against the stop plates 127 to shake the film holder 79 and dislodge any drops of liquid that may be hanging on the film or the holder. This occurs just as the traversing lug 105 is engaged with the traversing screw 69, so the drops fall back into the tank from which they come. When as many as several hundred film strips 41 are to be processed with one charge of chemicals, the savings achieved with this delayed-drain, final-snap action, are very significant.

As an incident to the raising of a film holder 79, the feed lug 104 is shifted away from the feed screw 68 and the traversing lug 105 is shifted into engagement with the traversing screw 69, so the carrier 65 immediately is advanced along the track bar 67 into alinement with the next tank. During such traversing, the coupling abutment 111 on the plunger 112 slides along the operating abutment 118 on the operating bar 117 to maintain the carrier in the film-raised position and in engagement with the traversing screw. The active thread section of the latter terminates with the feed lug 104 alined with the next feed section, so the carrier dwells in the raised position momentarily until the operator 110 is shifted back to the raised position to lower the film holder 79 into the next tank.

This engages the feed lug 104 with the next section of the feed screw 68 to initiate feeding of the carrier 65 relative to the new tank, thus shifting the plunger 112 axially past the trailing end of the operating abutment 118, into the space between adjacent abutments, and on toward the next abutment on the operator. After the selected interval, which may be for one dwell of the operator or for several, the plunger moves under the next operating abutment. If the selected time interval comprises more than one cycle of the operator, the plunger is disposed in the space between two operating abutments while the operator oscillates up and down,

and thus is not engaged during the intermediate oscillations. When the plunger eventually moves under an abutment 118 it is pushed down by the operator to raise the film holder 79 out of the tank, and thus repeats the traversing cycle.

It will be noted that the front face of each operating abutment 118 is relieved or beveled upwardly and rearwardly to cam the plunger 112 radially inwardly, toward the carrier body 75 against the action of the spring 114, in case the carrier is dwelling with the plunger in axial alinement with an operating abutment as the operator is raised to the pick-off position. This permits the operating abutment to raise past the plunger, which then snaps back outwardly under the abutment, ready for the next downstroke of the operator. In most instances, the timing of the feed sections of the feed screw 68 can be correlated with the timing of the oscillations of the operator 110 so that the plungers are fed under the operating abutments while the latter are raised in the pick-off position. In addition, the last convolution of each feed section preferably is of sharper pitch to "kick" the carrier rapidly into position to be engaged by the operator. The yieldability of the plunger thus should be considered primarily as a highly desirable safety feature rather than an essential element of the processor. In addition, it contributes to the ability of the processor to connect itself it, for any reason, the operator should miss a plunger during its downstroke.

THE RETURN AND STORAGE TRACK

The storage and return track 70 also is formed by an elongated, generally cylindrical bar which is approximately the same diameter as the track bar 67 so as to support the carriers 65 slidably on the processor 10. The return bar, however, is shorter than the track bar and has free ends spaced from the end walls 62 and 63 of the frame to provide a gap adjacent each wall through which carriers are moved vertically into and out of alinement with the return bar to permit the carriers to be transferred to and from the bar at the ends

Herein, the return bar 70 is supported between its ends on a rail 150 extending between the end walls 62 and 63 and secured at its ends to the end walls by brackets 151 and bolts 152, the return bar being attached to the rail by an elongated rib 153 which is substantially narrower than the diameter of the return bar and projects upwardly from the front edge of the rail to the underside of the return bar. With this arrangement, the carriers can be telescoped onto the return bar to slide thereon with the rib 153 extending into the carrier bodies through the downwardly opening slots 78 therein.

To minimize frictional resistance to movement of carriers 65 along the return bar 70, rollers 154 are telescoped onto the plungers 112 adjacent the ends of the latter and loosely retained thereon by pins 155, and a cam track 157 is mounted on top of the rail 150 on an upstanding L-shaped plate 158 to overhang the rail behind the return bar in position to engage the upper sides of the rollers and to hold the carriers in a preselected angular position relative to the return bar, thereby preventing binding of the carrier bodies against the supporting rib 153. The rail, return bar, and cam assembly may comprise separate parts suitably secured

together, or may be made as an integral extrusion of metal such as aluminum, or of a suitable plastic.

THE TRANSFER DEVICES

At each end of the main track 67 is one of the automatic devices 71 and 72 for transferring the carriers 65 between the two tracks, the on-feed transfer device 71 at the left end, as viewed in FIG. 1, being operable to move carriers one by one from the left or exit end of the return bar to the left or entry end of the main track, as required by the operation of the photographic apparatus 44, and the off-feed transfer device 72 at the right end being operable to move carriers one by one from the exit end of the main track to the entry end of the return track, upon completion of the movement of the carriers along the main track and past the various treating stations of the processor 10. As will be seen hereafter, the carriers receive film strips 41 to be processed at the loading station 42 during the transfer to the main track, and processed film strips are discharged at the station 43 during, and as an incident to, the transfer to the return track.

As shown most clearly in FIGS. 1 and 3, the on-feed transfer device 71 comprises an elongated arm 159 pivoted at one end on a pin 160 on the end wall 62 of the frame adjacent the front edge of the wall for swinging of the free end of the arm along the wall about an axis parallel to, and equidistant from, the two track bars 67 and 70. The arm extends rearwardly from the pivot pin and the free end is swingable up and down between raised and lowered position in which it is aligned with the respective track bars. A bracket 161 on the end wall cradles the arm and forms a stop determining the lowered position, as shown in broken lines in FIG. 3, and a second stop 162 abuts against the top of the arm to determine the raised position.

Mounted on the left side of the arm 159 adjacent the free end, perpendicular to the arm, is a saddle 163 in the form of somewhat elongated, part-cylindrical member that has a longitudinal slot in its underside for fitting over the reduced diameter portion 73 at the entry end of the main track bar 67. The saddle has an arcuate outside surface of the same diameter as the track bar so as to fill the reduced-diameter portion when lowered onto the track bar and, in effect, to form a continuation of the bar. When the arm is raised, the saddle is aligned with the return track bar so that the outside surface forms a continuation of this bar in the gap between the bar and the end wall 62 of the frame.

Overhanging the left end portion of the saddle 163 is a holding flange 164 (FIG. 3) under which one end portion 165 (FIGS. 17 and 18) of the carrier body 75 is disposed when a carrier 65 is in position on the saddle for transfer to the main track bar 67. The flange and the underlying end portion of the carrier body are shaped to abut against each other and prevent rotation of the carrier about the saddle during the transfer, herein having opposed flat surfaces. Thus, the angular position of the carrier relative to the saddle is substantially fixed after the roller 154 on the plunger 112 drops away from the cam track 157, which extends beyond both ends of the return bar substantially across the gaps at the ends thereof.

While various types of actuators may be used to shift the on-feed arm 159 back and forth between its raised

and lowered position, herein a reciprocating actuator 167 (see FIGS. 3 and 25) in the form of another fluid-powered cylinder is mounted on the rear portion of the end wall 62, as shown most clearly in FIG. 3, in an upright position with its piston rod 168 extending upwardly out of the cylinder and connected to the arm 159 by a flexible cable 169, the cable being guided over pulleys 170 and 171 rotatably mounted on the upper portion of the wall, and extending downwardly to a connection 172 on the intermediate portion of the arm. When the piston rod 168 is retracted, as shown in FIG. 3, the transfer arm is held in the raised position to receive a carrier 65 from the return bar 70. As the piston rod is extended upwardly, the arm is lowered to the position shown in broken lines in FIG. 3. A weight 173 preferably is mounted on the free end of the arm to augment the weight of the arm and thereby insure that the arm responds promptly to the extending of the piston rod, and a magnet may be incorporated in the arm at 174 (FIG. 3) to attract the end plates 107 if a lateral latching force is desired.

Actuation of the cylinder 167 is controlled by a valve 175 (FIG. 25) operated by a solenoid 177 and suitable electric circuitry including a switch 178 (FIGS. 1, 3 and 28) mounted adjacent the free end of the arm with its switch arm 178a positioned to be engaged by a carrier 65 on the saddle 163, thereby moving the switch arm to signal the presence of a carrier preparatory to each downward, transfer stroke of the arm and to signal the feeding of the carrier onto the main track bar 67 preparatory to each upward or return stroke. Another switch 179 is mounted on the end wall 62 adjacent the upper stop 162 with its switch arm 179a positioned for engagement by a stud 180 on the transfer arm 159, when the latter is raised, thus being closed to signal the presence of the transfer arm in the raised position and being opened to signal the lowering of the arm. These switches, plus a third switch 181 actuated by the photographic apparatus 44 as a film-strip 41 is discharged, control the operation of the on-feed transfer arm.

With the foregoing arrangement, the holding of the transfer arm 159 in its raised position with a carrier 65 on the saddle 163 preparatory to being transferred to the main track 67 is dependent upon the pressurization of the pneumatic cylinder 167 to maintain the piston rod 168 retracted. Thus when the processor 10 is deenergized, as it will be during long periods of non-use, the cylinder releases the arm, which would drop prematurely if nothing were done to prevent it from doing so. To prevent such dropping, a gate 182 (FIGS. 3 and 15) in the form of one leg of a bell crank pivoted on the rail 150 at 183 (FIG. 15) normally is disposed beneath the plunger 112 of the carrier held on the saddle 163 so as to catch the plunger and prevent lowering of the transfer arm 159 when the processor is shut down. Since the carriers are locked against rotation about the saddle, the gate leg 182 holds the transfer arm close to the fully raised position until being moved out of the way. This is accomplished, upon demand, by a reciprocating electric motor 183 connected to the other leg of the crank to rock the latter clockwise (FIG. 15) and thereby retract the gate leg to an out-of-the-way position, the motor being energized and the cylinder 167 being activated simultaneously through a switch 184 to retract the leg and lower the transfer arm.

The off-feed transfer device 72 is shown most clearly in FIGS. 10 and 11 and is fundamentally the same as the on-feed device 71, comprising an elongated transfer arm 185 pivoted on a pin 187 on the end wall 63, parallel to the track bars, with a saddle 188 similar to the saddle 163 mounted on the side of the arm so as to swing from a lowered position overlying and filling the reduced diameter portion 74 (see FIG. 12) at the exit end of the main track bar 67, to a raised position aligned with the return track bar 70. This arm is a strip of angle iron with a flange 189 for overhanging a flat 190 (FIGS. 16 and 17) on the right end portion of the carrier body 75 when the carrier is fed onto the saddle in the film-raised position. A cylinder 191 on the rear portion of the end wall 63 has an upwardly extending piston rod 192 attached to a cable 193 that is trained around pulleys 194 and 195 on the end wall and extends downwardly to a connection 197 on the intermediate portion of the arm 185, so that retraction of the piston rod from the extended position shown in FIGS. 10 and 11 pulls the arm up to the raised position shown in broken lines in FIG. 10.

A bracket 198 is positioned on the end wall 63 to abut against the upper side of the arm 185 when the saddle 188 is aligned with the return track bar 70, thereby limiting the upward, transfer stroke, and the saddle rests on the reduced diameter portion 74 of the main track bar 67 to limit the downward return stroke, which is assisted by a coiled spring 199 stretched downwardly and rearwardly from the underside of the arm to a pin 200 behind the tanks. In addition, a signal switch 201 on the end wall adjacent the stop bracket 198 has a switch arm 201^a engageable with the transfer arm in the raised position, and another signal switch 202 on the free end portion of the transfer arm has an arm 202^a which is engaged by carriers 65 moving onto the saddle at the end of the main track bar.

UNLOADING THE HOLDERS

Automatic removal of film strips 41 from the carriers 65 is accomplished by a power-operated discharge mechanism indicated generally at 203 and best seen in FIGS. 1 and 19-21, wherein it will be seen that the discharge mechanism comprises a pair of side-by-side feed rolls 204 having horizontally spaced axles journaled on tabs 205 depending from the open underside of a hollow housing 207 mounted on the upper front corner of the end wall 63 by means of a bracket 208. The feed rolls 204 cooperate with a pair of vertically stacked feed rolls 209 in supporting an upper belt 210 centrally trained around the left roll 204 (see FIG. 20) and the upper roll 209, and in supporting a pair of lower belts 211 trained around the right roll 204 and the lower roll 209 on opposite sides of the plane of the upper belt. The belts ride in peripheral grooves in the respective rolls and project slightly beyond the peripheries of the rolls to crimp the film strips 41 between the belts for a positive gripping action. A motor 212 (FIGS. 19 and 21) drives the lower roll 209 of the upper pair clockwise (FIG. 20) to drive the belts in unison in the direction indicated by the arrows.

It will be seen in FIGS. 1, 19 and 20 that the film holder 79 of a carrier 65 being transferred from the exit end of the main track bar 67 to the overlying end of the return bar 70 raised up directly beneath the lower feed

rolls 204 so that the film strip 41 in the holder is centered between the two rolls. The opposite sides of the funnel-like upper end 80 of the holder are notched at 213 to permit the holder to be raised until the upper end of the film strip engages the rollers so as to be gripped between the belts and pulled up through the housing 207, as indicated in FIG. 20, when the rollers are rotated by the motor 212 to drive the belts. The motor may run constantly while the processor 10 is operating, or may be energized automatically for a brief interval in response to movement of the transfer arm 185 to the raised position.

To insert the film strip 41 positively in between the rolls 204, each carrier 65 is held on the saddle 188 in a manner that prevents downward swinging of the carrier arm from a preselected angular position relative to the saddle, but permitting upward swinging, and the adjacent end portion of the cam track 157 is positioned to engage the follower roller 154 on the carrier just before the transfer arm reaches the upper limit of its stroke. Accordingly, the cam track stops the follower roller as the transfer arm continues upwardly from the full line position in FIG. 19 to the broken line position, thus 25 rocking the carrier counterclockwise about the saddle to swing the carrier arm 83 upwardly to the broken line position. This produces a direct, upward movement of the film holder 79 beneath the feed rolls to the broken line position for positive insertion of the strip between the rolls.

All that is needed to permit such upward rocking of the carrier 65 is the relieving of the front portion of the flat 190 on the right end of the carrier body, herein to rounded shoulder as shown at 190^a in FIGS. 16 and 17. After unloading, the carrier is moved laterally, to the left in FIG. 1, out of the discharge position and along the return bar 70 toward the exit end of the bar, as permitted by the notches in the film holder. The roller 154 then rides along the cam track to hold the carrier in the raised position until it is fed back onto the saddle 163 of the on-feed transfer arm 159, loaded with a film strip 41, and lowered to the main track 67. A similar relief may be applied at 165^a (FIG. 17) on the front portion of the flat 165 on the other end of the carrier body 75 to rock the carrier downwardly and drop the film holder directly away from the guide 49 of the photographic apparatus 44 as the transfer arm 159 begins the downward transfer of the carrier to the main track.

RETURN TRACK CONVEYOR

As shown most clearly in FIG. 15, a reverse supply of several carriers 65 is provided on the return bar 70 to accommodate several film strips 41 produced by the photographic apparatus 44 in rapid succession so that it is never necessary to wait for completion of one strip before a second strip can be processed. For example, a total of ten or more carriers may be provided. To maintain the idle carriers properly positioned in readiness for use, a feed conveyor 214 is mounted on top of the frame along the rail 150 to move each carrier off the saddle 188 of the transfer arm 185 at the end of the up-stroke of this arm, and also to shift all of the carriers toward the opposite end of the return bar, feeding the terminal carrier at the other end of the bar onto the saddle 163 of the transfer arm 159 preparatory to loading of this carrier with a film strip to be processed.

In this instance, the feed conveyor 214 comprises an endless chain disposed in a horizontal plane immediately above the return bar 70 and trained around two sprocket wheels 215 and 217 rotatably supported on vertical shafts 218 and 219, respectively, upstanding from the upper edges of the two end walls 62 and 63. One run of the chain, herein the rear run 214a, overlies the return bar to constitute the active run of the conveyor, and the other run 214b is spaced forwardly from the bar in an out-of-the-way position. An abutment in the form of a depending pin 220 on the chain is engageable with the right ends of the carrier bodies 75 to move the latter to the left away from the right end wall 63 as the active run 214a moves to the left.

The left sprocket 217 (FIG. 15) is an idler sprocket that is journaled to turn about the shaft 219, and the right sprocket 215 is fast on the shaft 218, which is journaled on the end wall 63 and carries a smaller sprocket 221 on its upper end for driving the chain. Trained around the driving sprocket 221 is an endless chain 222 which also extends around a second sprocket 223 supported above the rear portion of the rail on the shaft of a reversible motor 224 (see FIG. 12) slung on the underside of the rail. When this motor is energized to turn its sprocket 223 counterclockwise as viewed in FIG. 15, the left conveyor sprocket 215 also is turned counterclockwise to drive the conveyor run 214a to the left, thereby moving the conveyor pin 220 to the left thereby moving the conveyor pin 220 to the left along the return bar. Reversal of the motor reverses the direction of the conveyor to return to the right to a starting position which herein is on the front run 214b of the chain adjacent the right sprocket 215, as shown in FIGS. 1 and 15.

Automatic control of the feed conveyor 214 is provided by the switch 201 mounted on the right end wall 63 with its switch arm 201a positioned to be engaged by the off-feed transfer arm 185 when the latter is raised, thus signaling the presence of a carrier in position to be fed onto the return bar, and by a switch 225 mounted on the upper edge of the right end wall with a switch arm 225a in the form of an elongated feeler positioned for engagement with the conveyor pin 220 as the latter moves to the left along the return run 214b of the chain, the feeler arm being released to close the switch as the pin moves forwardly (to the right) toward the sprocket 215 at the beginning of a feeding operation. When the switch 201 closes, the switch 225 being held open by the pin 220 in the start position, the motor 224 is started in the forward direction so that the pin feeds the carrier off the saddle 188 and onto the return bar 70, thus opening the switch 202 adjacent the saddle. This causes the transfer arm 185 to drop back down to the main track bar 67, operating switch 201 so that the forward winding of the feed motor is deenergized and the reverse winding is energized. Accordingly, the conveyor 214 is driven reversely until the pin 220 is returned to the start position, opening switch 225 to terminate reverse operation.

Each time the photographic apparatus 44 is activated to expose a film strip 41, switch 181 on the upper edge of the left end wall 62 is operated to initiate sustained forward operation of the feed motor 224 whenever the on-feed transfer arm 159 is raised to receive a carrier, as sensed by the switch 179 above this arm. Thus, the

pin 220 is driven to the left along the return track 70 to engage the body of the carrier at the right end of the reserve stack and feed the entire stack to the left. As the carrier at the left end of the stack moves onto the saddle 163 of the on-feed transfer arm, the switch 178 on the arm is closed, and this initiates sustained reverse operation of the feed motor until the conveyor pin 220 is returned to its start position and opens the switch 225.

To prevent the lifting of a carrier 65 from the main track bar 67 to the end of the return track bar 70 while the conveyor pin 220 is on the active run 214a of the chain, a sensing switch 227 (FIGS. 15 and 28) is mounted on the upper edge of the right end wall 63 with an operator in the form of a rocker positioned to be engaged by the conveyor pin in both directions of its movement around the conveyor sprocket 215. When this rocker is tilted forwardly relative to the pin motion, signaling that the conveyor pin is out of its start position, the actuating circuitry of the off-feed transfer arm 185 is disabled to delay the transfer of the next carrier until the conveyor pin has returned. Then, as the pin moves back around the sprocket 215 toward the start position, it shifts the rocker rearwardly to activate the circuitry of the transfer arm so that the next carrier can be lifted to the return bar. It will be evident that this is a safety interlock for eliminating the possibility of jamming of the feed conveyor 214 under a set of circumstances that could occur during repetitive operation of the processor.

THE FLUID SYSTEM

Reference has been made, in general, to many of the electrical and fluid-actuated components for controlling the operation of the processor. The schematic representation of the fluid system in FIG. 25 shows the basic elements and flow lines or tubes of a workable pneumatic system in which the output of a compressor 228, hereafter called the pump, is delivered through a line 229 to a hollow column 230 serving as a manifold and as means for smoothing out any pulses created by the pump. From the column, a pressure tube 231 leads to the valve 175 controlling the flow for the left transfer cylinder 167, the lower end of this cylinder being connectible to the pressure tube 231 through a tube 232 from the valve 175, and the upper end being connectible to the pressure tube through a tube 233. The solenoid 177 controls the condition of this valve to determine whether the piston rod 168 is extended or retracted.

A pressure tube 234 leads to a similar valve 235 for the right transfer cylinder 191, the opposite ends of which are connectible to the valve through tubes 237 and 238. A solenoid 239 controls the position of this valve.

A third pressure line, the tube 135, extends from the column 230 to the valve 129 controlling the cylinder 121 for oscillating the operating bar 117 back and forth between its raised, pick-off position and its lowered, traversing position. The line 135 from this valve, which is controlled by solenoid 132, leads to the upper end of the cylinder 121, and the line 130 leads to the lower end. Each of the transfer cylinders 167 and 191 is shown as having a needle valve 240 at each end for controlling the rate of flow of air to and from the

cylinder, thereby to set the rate of movement in each direction.

THE ELECTRICAL SYSTEM

As shown in FIG. 28, the electrical components herein are arranged to be connected across two power lines 241 and 242 for activation when a master on-off switch 243 is closed by a relay 244 controlled by the coin mechanism 55. It will be seen that the pump motor 245 is energized continuously through a line 247 when this switch is closed. Immediately below the pump circuit in the diagram is the control for the reversible conveyor motor 224, the forward and reverse windings 248 and 249 being in parallel lines 250 and 251, respectively, adapted to be connected alternately by switches 178, 179, 181, 201 and 225 to a line 252 to drive the conveyor 214 in appropriate directions at appropriate times during the operation.

Below the conveyor circuits is the circuit 253 for the solenoid 239 which controls the valve 235 to raise the off-feed arm 185 when switches 202 and 227 are closed, and below this is the circuit 254 for the motor 101 driving the lead screws 68 and 69, this motor also being energized when the on-off switch 243 is closed.

Continuing downwardly in the wiring diagram, the next group includes the timing motors 133 and 134 which are in parallel lines 255 and 257 and are adapted to be activated alternately as two switches 258 and 259 are alternately opened and closed, these switches being mounted on the end wall 62 for actuation by the operator 110, as shown in FIG. 3. When the operator is raised, the bar 117 engages the arm 258a of switch 258, closing the switch so that the up timer motor 133 is energized to time the dwell at the top of the stroke before opening a timed switch 260 (FIG. 28) and energizing the solenoid 132 to initiate the down stroke. When the lower switch 259 is closed at the end of the down stroke, the down-timer motor 134 is energized to hold its switch 261 in the full-line position in FIG. 28 for a selected interval thereby to time the dwell of the operator at the bottom of the stroke before solenoid 132 is deenergized by movement of switch 261 to the broken-line position to initiate the up stroke. Timed switch 260 then delays resetting of timer motor 134 during the dwell in the up position, and is opened to initiate the next down stroke.

The lower portion of FIG. 28 contains the activating circuitry for a main timer 262 which is energized upon closure of a start switch 263 at the beginning of the photographing operation, and controls four timed switches 264, 265, 267 and 184, the switch 264 completing a holding circuit for the timer 262 as soon as the latter is started, and the remaining switches being closed and then opened in a timed sequence related to the delivery of a film strip 41 to the loading station 42. Switch 265 closes after a timed interval for the taking of the photographs, and activates the cut-off motor 54 to sever the strip of exposed film. Then switch 267 closes to activate the feed rolls 50 of the photographic apparatus and thereby feeds the severed strip through the guide 49 for insertion in a carrier 65.

Switch 184 then closes after the strip is in the carrier, and prepares a circuit through a line 268 to the solenoid 177 for initiating a downstroke of the on-feed transfer arm 159, and to the solenoid 183 for the carri-

er release gate 182. A switch 270 mounted on the end wall 63 (FIGS. 10 and 11) has an elongated arm 270a that is engaged by the operating bar 117 as the operator 110 moves down, and thus is closed to signal that the operator is in its lowered position. This completes the circuits for the solenoids 183 and 177 to initiate the processing cycle by dropping the loaded carrier 65 to the entry end of the main track bar 67, after which processing continues automatically to completion under the control of the lead screws 68 and 69, the operator 110 and the various sensing and signaling switches.

SUMMARY OF OPERATION

While the automatic operation of the processor 10 will be readily understood by those skilled in the art in view of the foregoing detailed description of the various components of the machine, including the specific descriptions of the functions thereof, the following general summary of operation should aid in the complete understanding of the overall sequence of operations. Assuming that the apparatus is deenergized but ready for operation with all of the carriers 65 stored on the return bar 70 and the pump motor 245 and the screw motor 101 shut off, the on-feed transfer arm 159 is held in the raised position above the left end of the track bar 67 by the gate 182, ready to receive a carrier, and the off-feed transfer arm 185 is lowered onto the right end of the track bar, ready to receive a carrier after processing of a film strip 41. The operator 110 is lowered.

When a customer inserts a coin of the required denomination in the coin mechanism 55, the latter activates the photographic apparatus 44 to make the selected number of exposures in the sequence for which the apparatus is programmed, including an initial time delay, turning on of the lighting in the booth, actuation of the camera, and feeding of the film between exposures. During this period, the relay 244 is energized to close the on-off switch 243 and thereby activate the control circuitry of the processor 10, starting the pump motor 245 and the screw motor 101 and preparing the other circuits for automatic operation. The photographic apparatus 44 closes switch 263 in the circuit of the timer motor 262, which thus is started and closes its switch 264 for the holding circuit around the start switch 263. The photographic apparatus also moves switch 181 from its normal position shown in full in FIG. 28 to the position shown in broken lines, and the on-feed transfer arm 159 is raised by the cylinder 167 to close switch 179. Since there is no carrier on this arm, switch 178 is in the position shown in full in FIG. 28 to complete a circuit through switches 181, 179, 178 for the forward winding 248 of the conveyor motor 224, which thus begins to drive the conveyor 214 forwardly to shift the stack of carriers 65 on the return bar 70 to the left until the leading carrier is fed onto the saddle 163 of the raised on-feed arm.

Switch 178 immediately is changed to the broken-line position in FIG. 28 to reverse the energization of the motor 224 through switch 225, which is closed while the conveyor pin 220 is spaced from its retracted position. This reverses the conveyor 214 to return the pin 220 to its retracted position, in which switch 225 is opened, thereby deenergizing the conveyor motor 224.

After a suitable delay, switch 181 is returned to the full-line position in FIG. 28.

While the foregoing is occurring, the photographic process is completed on a timed schedule, and the film strip 41 is ready to be severed for processing. Timer motor 262 closes its switch 265 to activate the cut-off 54, and then closes its switch 267 to activate the feed rolls 50 and deliver the severed film strip 41 to the carrier 65 that has been positioned on the on-feed arm 159. Then switch 184 is closed by the timer to prepare the circuits for the solenoids 183 and 177 controlling the gate 182 and the cylinder 167 for the on-feed arm 159 for transfer of the carrier to the track bar 67.

Simultaneously with the foregoing, of course, energization of the pump motor 245 results in the pressurization of the fluid system and initiation of timed oscillation of the operator 110 under the control of the timer motors 133 and 134 and switches 258 and 259. At the beginning, the operator 110 is in the lowered position and switch 259 is closed, so that the closing of on-off switch 243 immediately completes a circuit through switch 259 for the timer motor 134. Simultaneously, a second circuit for the solenoid 132 is completed through a line 273 and switch 261. The switch 261 is in the full line position in FIG. 28 when the timer 134 is activated.

Accordingly, energization of the solenoid 132 shifts the valve spool 137 (FIG. 26) to the right to the broken line position so that fluid under pressure is delivered from pressure line 135 to line 131 leading to the upper end of cylinder 121. The operator is held down while the timer motor 134 times out and shifts switch 261 to the broken line position (FIG. 28), thereby breaking the energizing circuit for solenoid 132 and returning the valve spool 137 to the full-line position (FIG. 26) so that the pressure line 135 communicates with the line 130 to the lower end of the cylinder and causes the cylinder to raise the operator and open switch 259.

At the upper end of the stroke, the operating bar 117 closes switch 258 to energize timer motor 133, which times the swell in the raised position before opening its switch 260. It will be seen that this switch is in an alternate, holding circuit for timer motor 134, including lines 271 and 272, when switch 261 is in the broken-line position, so that opening of switch 260 by timer motor 133 resets time motor 134 to shift switch 261 back to the full-line position. This re-energizes solenoid 132 to cause the operator 110 to be lowered, opening switch 258 to reset timer motor 133 and closing switch 259 to start timing the next dwell of the operator in the lowered position. Thus, the operator continues to move up and down.

As the operator 110 moves down for the first time after the film strip 41 is delivered to the waiting carrier 65, switch 270 is closed to complete the on-feed circuits and drop the on-feed arm 159 to the entry end of the track bar 67. The saddle 163 thus is shifted onto the reduced diameter entry portion 73 so that the traversing lug 105 engages the first section 69^a of the traversing screw 69 while the coupling abutment 111 is dropped under the first operating abutment 118 of the lowered operator 110. Thus, the carrier is traversed along the screw 69 to advance the carrier to the right, off the saddle and onto the track bar 67, and then rotates about the track bar to lower the film holder 79

into the first tank as the operator 110 is raised the next time.

This, of course, shifts the follower lug 104 into engagement with the first feed screw section 68^a to begin feeding the holder 79 through the first tank at the selected feed rate for this tank, and feeds the coupling abutment 111 into the space between the first two operating abutments 118 so that the carrier remains in the film-lowered position during subsequent down strokes of the operator 110 and until completion of the selected interval for treatment in the first tank.

During such feeding, the follower lug 104 rides against the first feed screw section 68^a and is shifted up and down by the screw 68, which is rotating eccentrically about its axis for the desired agitation of the holder 79 in the tank. This continues until the feed screw advances the carrier along the track 67 into axial alignment with the next operating abutment 118 on the operator 110 while the latter is raised, the selected interval being a multiple of the interval selected for each cycle of the operator and ranging from one cycle to as many as are needed for the processing step.

As the follower lug 104 approaches the end of the screw thread on the first feed section 68^a, the increased end pitch of the thread accelerates the carrier 65 to feed the plunger 112 under the next operating abutment 118, moving the follower lug 104 into the gap (FIG. 14) at the end of the screw section. If the coupling abutment 111 should happen to be above the operator at this time, the cooperating cam surfaces adjacent the abutments press the plunger in to permit the operator to pass, and the spring 114 then snaps the plunger back out beneath the operating abutment preparatory to the next down stroke.

As this stroke begins, the plunger 112 is pressed downward to rock the film holder 79 upward and lift the holder out of the liquid in the tank, thereby disengaging the follower lug 104 from the feed screw 68. The control valve 129 initially permits fluid to be exhausted from the cylinder 121 at a relatively rapid rate through the groove 148 (FIG. 27) in the valve plunger 141 so that the raising motion is at a selected relatively rapid rate until the holder is clear of the liquid in the tank. Then the operator 110 engages the head 145 of the valve plunger and shifts the groove 148 therein out of the bleed passage 142 to reduce the exhaust rate to that set by the needle 139, nearly stopping the raising motion for the momentary pause of the holder over the tank for drainage.

The continued slow motion of the operator 110 then moves the first of the plunger grooves 149 into alignment with the bleed passage 142, removing the restriction and restoring the rapid rate for the remainder of the down stroke of the operator. This snaps the film holder 79 upwardly while moving the follower lug 105 into engagement with the traversing screw 69 and slapping the supporting arms 119 of the operator against the lower stops 127 to dislodge any drops of liquid clinging to the holder 79 while the latter is over the tank.

While the operator 110 dwells in the lowered position and holds the carrier 65 in the film-raised position, the traversing screw 69 shifts the carrier along the track bar 67 toward the next feed screw section and moves the carrier across the space between adjacent tanks

into alignment with the beginning of the second tank. The follower lug 105 dwells at the end of the traversing section with the plunger 112 near the end of the coupling abutment 118 until the operator is raised, thereby lowering the film holder 79 into the aligned tank and reengaging the follower lug 104 with the feed screw 68, this time with the second feed screw section 68b, which feeds the carrier along the track bar 67 to shift the plunger out from beneath one operating abutment and into the gap between two abutments.

This processing continues as the carrier 65 is advanced relative to successive tanks and the holder 79 is fed through each tank at a rate that is selected to provide the selected time interval of treatment before the coupling abutment 111 on the plunger 110 moves into the path of the next operating abutment 118. At the end of each such interval, the holder is raised out of a tank, drained, snapped, and then traversed into alignment with the next tank preparatory to being lowered into the tank. Any desired number of steps, and any desired combination of intervals may be provided by the spacing and pitches of the feed screw sections, the rate of rotation of the feed screw, and the timing of the cycles of the operator.

As the carrier is rotated to the film-raised position at the end of the last tank, the flat 190 on the carrier body 75 is turned into alignment with the underside of the flange 189 on the off-feed arm 185 which, of course, is disposed in the lowered position with its saddle 188 on the reduced-diameter portion 74 of the track bar 67. Then the follower lug 105 is engaged with the last thread section 69^a of the traversing screw 69 and the carrier is driven onto the saddle. This immediately closes the switch 202 on the off-feed arm 185 to energize the solenoid 239 and cause the piston rod 193 of the cylinder 191 to be retracted, thereby raising the saddle and the carrier toward the gap at the right end of the return bar 70. Just before the arm reaches its raised position, the follower roller 154 engages the cam track 157 and causes the carrier to rock the holder 79 directly upward and thereby lift the upper end of the film strip 41 into the discharge rollers 204, as shown in FIG. 20. These rollers and the belts 210 and 211 grip the strip and feed it out of the processor 10 for delivery to the customer as the carrier is moved into alignment with the return bar.

At the same time, the transfer arm 185 moves the arm 201a of switch 201 to the broken-line position in FIG. 28 to signal the arrival of the carrier 65 at the end of the return bar 70, and this immediately completes a circuit for the forward winding 248 of conveyor motor 224 through switch 181, switch 201, and a line 275 bypassing switch 178. The conveyor 214 thus is driven forward to advance the pin 220 from its retracted position into engagement with the carrier 65 to shift the latter off the saddle 188 and onto the return bar 70 after a short time delay for unloading. With the removal of the carrier, switch 202 is opened to drop the transfer arm 185 back to the track bar 67, and this causes switch 201 to change back to the full line position in FIG. 28, reversing the conveyor motor 224 through switch 225 until the pin 220 returns to its retracted position. Then switch 225 is opened to deenergize the motor.

The control for relay 244 maintains the processor circuitry energized for an appropriate interval for completion of processing each film strip 41 through the machine, and may be used to shut down the machine automatically during periods of non-use. It will be evident that there is no problem with the processing of successive strips at closely spaced intervals because each strip's movements are completely independent of, and unrelated to, the movements of successive strips through the processor, and because the feed and traversing screw sections are capable of handling successive carriers in closely spaced relation, even to the extent of permitting two strips to be in one tank at the same time.

As previously stated, the rocker switch 227 that is moved back and forth by the conveyor pin 220 as the latter moves to and from its retracted position disables the off-feed solenoid 239 while the pin is away from the retracted position. This prevents one carrier from being raised to the return bar 70 in back of the conveyor pin, as might occur when a new strip is about to be exposed and a previously exposed strip is just completing its processing. Thus, the carrier with the processed strip is simply held momentarily at the end of the track bar 67 until after an empty carrier has been fed onto the on-feed transfer arm 159 and the pin 220 has been returned to the retracted position to close the rocker switch 227.

PROTECTION OF CHEMICALS AGAINST AERATION

Illustrated in FIGS. 4-6 is an important secondary feature for protecting one or more of the chemicals against excessive exposure to air while in the tank, some chemicals such as developers being adversely affected by aeration. The open upper end of the first tank is partially covered by fixed insets 277 and 278 which leave uncovered an entry area 279 through which the holders 79 are lowered into the tank, an exit area 280 through which the holders are raised out of the tank, and a connecting passage 281 for movement of the depending portion of each carrier arm 83 across the tank during feeding. The insets preferably have beveled upper surfaces 282 and 283 facilitating insertion of the holders, and cover the remainder of the areas of the liquid to prevent unnecessary aeration. It has been demonstrated that this can increase the useful life of developing chemicals significantly and thus reduces operating and servicing costs. This tank is shown as a small compartment in one corner of the second tank to illustrate the versatility of the machine with respect to different volume requirements.

SERVICING OF THE PROCESSOR

As shown most clearly in FIGS. 3, 10 and 12, the row of tanks herein is supported on a front section of the bottom wall 64 of the frame forming a slide 284 having one or more laterally projecting anti-friction rollers 285 on each side guided in a track 287 fast on the adjacent end wall 62, 63, and also having a pair of rollers 288 beneath the front edge of the slide for rolling on the floor or other support 289 for the processor. Thus, the tanks can be pulled out of the frame from the normal position beneath the path of the carriers 65 to a servicing position shown in broken lines in FIG. 3, for easy access to the tanks during servicing.

Servicing of a processor 10 of the foregoing type requires periodic replacement of the chemicals, and this machine. To expedite such servicing, the tanks herein are joined together into at least one tank unit comprising several integrally connected tanks, two such units 290 and 291 being provided as shown in FIGS. 1 and 15, each comprising about one-half of the tanks. A special servicing cover 292 (FIGS. 22-24) is provided to be positioned and latched on, and thus attached to, each tank unit. This cover has a central handle 293 for lifting the cover away from the temperature-controlling jacket 66, and also has manually operable latches 294 engageable with lugs 295 on the tank unit to join the two together so that the tank unit can be lifted with the cover. The placement of the cover and the latching operation are shown in FIG. 23, and the latched condition is shown in FIG. 24, wherein it will be seen that the tanks project upwardly beyond the jacket and the cover has a foam lining 297 that is drawn down into tightly sealed relation with the upper edges of the tanks as an incident to the latching operation.

Thus, servicing is reduced to the simple operation of shifting the slide 284 to the servicing position, placing and latching the cover 292 on a tank unit containing chemicals to be renewed, lifting the tank unit out, and replacing it with a similar unit containing fresh chemicals. The replacement unit also is handled by means of a cover 292 latched thereon. Then the slide is pushed back in place and the on-site chemical servicing is completed, expeditiously and without the mess of mixing and pouring chemicals on the site. The tank unit containing exhausted chemicals can be carried back to the laboratory for emptying, disposal of the chemicals, cleaning, and refilling, with much greater convenience than if the entire changeover were performed at the location of the machine, as well as with the greater accuracy and efficiency possible with laboratory equipment and quantity preparation. The result is a very significant saving in servicing costs.

MODIFIED FORM

It is important for processors that are to be used in automatic self-photography machines to be compact enough to pass easily through standard doorways, and in this respect, the width of the processor 10 is a very important consideration. Moreover, existing cabinets are designed to receive a relatively narrow processor, but could accommodate greater height or front-to-rear depth. If it should be deemed desirable, for any reason, to increase the travel of the carriers 65 to a distance greater than the spacing of the end walls 62 and 63, this may be accomplished by adding a second processing track 298 spaced from the main track 67 and the return track 70. Such a modification is illustrated generally in FIGS. 29 and 30 to suggest one way that this can be done.

It will be seen in FIG. 29 that the modified processor 40' has a frame with a central shelf 299 supporting a row of processing tanks 300 approximately midway between the upper and lower ends of the frame. Above the shelf is a second shelf 301 having an upstanding support 302 mounting a bar for the track 298 from below so that the ends of this bar are free, basically in the same manner as has been described for the return bar 70. Beneath the shelf 299, a second row of tanks

303 is supported on a bottom wall 304 with a track bar 305 adjacent the tanks and supported from its ends, in the manner of the main track bar 67 of the first embodiment. Each of the track bars has a feed screw 307, a traversing screw 308, an oscillating operator 309, and a control valve 310 similar to the valve 129, together with signal switches, actuators and controls similar to those in the first embodiment so that carriers 65 can be processed along each of these bars and past both rows of tanks 300 and 303. Switches, actuators and other parts corresponding to those in the first embodiment, but not specifically described, are indicated by corresponding, primed reference numbers.

Above the upper track bar 298, a storage bar 310 is mounted on a third shelf 311 in substantially the same manner that the return bar 70 of the first embodiment is mounted on the rail 150, with a modified chain conveyor 312 for moving carriers 65 along the storage bar. The carriers themselves are the same as those in the first embodiment.

The primary difference, in addition to the third bar 310, is the lengthening of the transfer arms 313 and 314 that are pivoted on the end walls 315 and 317 of the frame, and the positioning of all three track bars 298, 305 and 310 equidistant from the pivotal axes of the arms, which thus are movable from positions overlying the reduced-diameter portions of the lower bar 305, through intermediate positions alined with the middle bar 298, and into positions alined with the upper bar 310, the three positions of each arm being shown in different types of lines in FIGS. 29 and 30. Thus, carriers may be transferred from one end of the storage bar 310 to the adjacent end of the middle bar 298, processed along the middle bar to the opposite end, dropped to the lower bar 305, and processed through a second series of steps in moving back along the lower bar. Then the carriers can be raised all the way back to the storage bar 310 preparatory to re-use. Cylinders 318 and 319 and cables 320 and 321 are provided to actuate the transfer arms, and suitable controls (not shown) for the cylinders are provided to actuate the cylinders and obtain the desired sequence of transfer motions. If a third processing track (not shown) is added, above and similar to the middle track 298, a three-level processor with a fourth storage and return level is provided for even greater processing capacity, and having the full-evident to those skilled in the art that separate transfer devices may be used for each of the additional levels as in the first embodiment, if desired, but that the arrangement disclosed in FIGS. 29 and 30 has the advantage of reducing the number of parts required.

From the foregoing, it will be evident that the present invention provides a highly versatile and operationally flexible processor that may be adapted for any desired automatic sequence of processing operations, comprising processing steps of preselected timed duration, individually adjustable according to the specific requirements of each step, with positive feeding and agitation of the carriers 65 during the various steps for optimum liquid contact, controlled lifting of the film holders 79 out of each tank for drainage of liquid back into the tank, and snapping of the holders into the raised position to dislodge any clinging drops of liquid before the carrier is moved on to the next tank. The basic time

cycle determined by the cycle of the oscillating operator 110 is selected so that multiples of this cycle provide the longer cycles for longer treating intervals, and the pitches of the various feed screw sections are selected to produce each desired time interval. Moreover, the pitches, lengths and positions of the traversing screw sections are similarly flexible, as are the positions of the operating abutments 118 along the bar 117 of the operator 110.

The transfer devices 71 and 72 cooperate with the return bar 70 and its conveyor 214 in providing the full-loop path for completely automatic cyclical operation, the transfers between the adjacent ends of the tracks being made possible by the manner of supporting the track bars with the ends of at least one bar free for movement of the transfer arms 159 and 185 into and out of the gaps at the ends of the bar. In short, the several features of the present invention provided a unique processor that is eminently well suited for an automatic process of the type required for color film.

It also will be apparent from the foregoing that, while a particular form of the invention has been illustrated and described, and a specific use suggested, various modifications and other uses can be made without departing from the spirit and scope of the invention.

I claim as my invention:

1. An automatic film processor having, in combination:

a box-like frame having spaced upright end walls and a bottom wall;
a cylindrical track bar extending horizontally between said end walls above said bottom wall and having reduced diameter end portions adjacent said end walls forming an entry end for said track bar adjacent one end wall and an exit end for the track bar adjacent the other end wall;
a series of tanks disposed side by side in a row along said bottom wall and having open upper ends spaced apart longitudinally of said track bar;
a return bar spaced above said track bar and having free ends spaced from said end walls to leave gaps overlying said reduced-diameter portions;
means supporting said return bar on said frame, including a rib narrower than the return bar connected to the underside thereof;
a plurality of carriers having bodies formed with openings shaped to fit around said bars and support the carriers slidably on the bars, arms projecting outwardly from said bodies to overhang said tanks, and holders on said arms for film strips to be processed through said tanks;
said bodies being rotatable about said track bar between spaced angular positions to lower said holders into said tanks in one angular position and to raise the holders above the tanks in the other angular position, said carriers normally being stored in a row on said return bar;
first and second transfer arms pivoted on said end walls to swing about axes parallel to, and equidistant from, said bars, said transfer arms having means thereon for transferring carriers from said return bar to said track bar at said entry end for processing of a film strip along the track bar, and for transferring carriers back to said return bar at said exit end after such processing;

an elongated feed screw extending along one side of said track bar and having a series of axially spaced feed screw sections thereon of differing pitches, each of said sections being positioned to feed carriers past one of said tanks;

an elongated traversing screw extending along the other side of said track bar and having axially spaced traversing screw sections thereon spanning the spaces between the adjacent ends of said feed screw sections and between said tanks;

follower means on said carrier bodies for engaging said feed screw when said bodies are in said one angular position and engaging said traversing screw when said bodies are in said other position;

means operating on a timed sequence to shift each carrier on said track bar to said one angular position at the leading end of each of said feed screw sections to feed said holders through said tanks, and to said other angular position at the trailing end of each feed screw section for traversing of said holders between tanks, thereby cooperating with said screws to advance each carrier along said track bar and move the holder of the carrier through successive tanks along said path;

and means for returning carriers along said return bar for re-use.

2. An automatic film processor as defined in claim 1 in which said transfer arms have saddles of arcuate cross-section projecting laterally from their free end portions and movable onto said reduced-diameter portions for transfers to and from said track bar, said saddles being movable into said gaps in axial alignment with said return bar for transfers to and from the latter.

3. An automatic film processor as defined in claim 2 in which said transfer arms and said carriers have opposed surfaces for holding the carriers in a preselected angular position during the transfers.

4. An automatic film processor as defined in claim 3 in which one of said screws has end sections for feeding carriers off one saddle and onto said track bar at said entry end, and off said track bar and onto the other saddle at said exit end.

5. An automatic film processor as defined in claim 4 in which said carriers are transferred to and from said track bar with said bodies in said other angular position, and said traversing screw has said end sections for feeding the carriers to and from said saddles.

6. An automatic film processor as defined in claim 2 including a fluid-activated operator for moving said first transfer arm back and forth between said bars at said entry end, and further including a gate mechanism for mechanically blocking movement of said first arm from a raised position adjacent said return bar and actuated with said operator to release the first arm for movement toward said entry end, whereby said gate mechanism maintains said first arm in said raised position when said operator is deactivated.

7. An automatic film processor as defined in claim 2 in which said second transfer arm is movable between said exit end and the overlying end of said return bar, and has means thereon for holding said carrier against downward rotation during the transfer motion, and further including a discharge device disposed above the position of the holders adjacent the upper end of said transfer motion to receive the upper ends of film strips

prior to movement of the carriers off the saddle and onto said return bar.

8. An automatic film processor as defined in claim 7 further including a stop engageable with each carrier adjacent the upper end of said transfer motion and operable to rotate the carriers to swing the holders upwardly as the transfer motion is completed, thereby to raise each film strip into said discharge device.

9. An automatic film processor as defined in claim 1 in which said feed screw comprises a central shaft journaled on said frame for rotation alongside said track bar, a plurality of tubular sleeves telescoped onto said shaft in end-to-end relation with said feed screw sections on said sleeves, and means holding said sleeves on said shaft for rotation therewith.

10. An automatic film processor as defined in claim 9 further including an annular shoulder between each pair of adjacent sleeves forming a stop for limiting movement of said follower means at the end of each feed screw section, the latter terminating short of the shoulder to permit the carriers to dwell relative to said feed screw.

11. An automatic film processor as defined in claim 1 in which said follower means include a lug on each carrier body radially spaced from said track bar and riding against said feed screw when the body is in said one angular position on the track bar with the holder in one of said tanks, said feed screw being arranged to shift said follower lug radially in and out thereby to agitate the holder up and down in the tank as the holder is fed through the tank.

12. An automatic film processor as defined in claim 11 in which said feed screw is eccentrically journaled on said frame to act through said follower lug in agitating said holder up and down during each revolution of the feed screw.

13. An automatic film processor as defined in claim 1 in which said operating means include a plurality of operating abutments spaced apart longitudinally of said track bar on one side thereof and supported for back and forth movement in unison in planes generally perpendicular to the track bar, one of said abutments being provided for each space between two adjacent tanks, power-operated means for moving said abutments periodically back and forth through active and return strokes between two spaced positions, and a coupling abutment on each of said carriers positioned to be engaged by one of said operating abutments during said active strokes when the carrier is at the end of one of said feed screw sections and to be moved about said track bar in a manner to shift the carrier body to said other angular position, said coupling abutments being disposed between adjacent operating abutments when said follower means are engaged with one of said feed screw sections.

14. An automatic film processor as defined in claim 13 in which said abutments are supported on an elongated operating bar mounted for oscillation about the longitudinal axis of said track bar in parallel therewith between raised and lowered positions on the side of said track bar remote from said holders, and said coupling abutments are spaced outwardly from said track bar to be disposed under successive abutments when the operating bar is in said raised position, thereby to be lowered and to raise the holder on the

carrier as said operating bar is moved through said active stroke to said lowered position.

15. An automatic film processor as defined in claim 13 in which each of said carriers has a plunger projecting outwardly from one side thereof to move into the paths of successive operating abutments as the carrier moves along said track bar, the outer end portion of said plunger carrying the coupling abutment on one side of the plunger and being spring-urged outwardly, said plunger and said operating abutments having coacting cam surfaces causing said plungers to yield inwardly to permit the operating abutments to pass the plungers in moving in one direction into position to engage the coupling abutments.

16. An automatic film processor as defined in claim 13 in which said power-operated means include a power actuator, means controlling the actuator to cause said operating abutments to dwell for a first preselected time interval in one of said spaced positions before being moved through said active stroke, and also controlling the actuator to cause said operating abutments to dwell for a second preselected time interval in the other of said spaced positions before being moved through said return stroke.

17. An automatic film processor as defined in claim 16 further including means controlling the active strokes of said operating abutments to cause the latter to pause momentarily with the holder of a carrier above a tank before completing said active stroke, thereby to permit drainage of liquid back into a tank before engaging said traversing screw and advancing the holder into alignment with the next tank.

18. An automatic film processor as defined in claim 17 in which said means for controlling said active strokes also cause the actuator to complete the active strokes with a snap action after the momentary dwell, thereby to shake the holders to separate any drops of liquid clinging thereto.

19. An automatic film processor as defined in claim 1 in which said tanks are joined together to form at least one tank unit comprising a plurality of tanks, and further including:

means supporting said tank unit for movement on said frame between a treating position generally beneath said track bar and a servicing position spaced laterally from said treating position, a cover adapted to be placed over said tank unit and having a lifting handle thereon, and means for releasably securing said cover to said unit in order to lift the latter out of said frame during servicing of said processor.

20. An automatic film processor as defined in claim 19 in which said tank-supporting means include a slide movable between said treating and servicing positions, and a temperature-controlling jacket on said slide having an open upper side for receiving said tank unit into said jacket.

21. An automatic film processor as defined in claim 1 further including a cam track extending along said return bar in spaced relation therewith, and a follower roller on each of said carriers engageable with said cam track to hold the carrier in a preselected angular position about said return bar during movement thereon, said cam track extending at least partially across said gaps to maintain said carriers in said preselected angular position.

lar position as the carriers are moved onto and off of said transfer arms.

22. An automatic film processor as defined in claim 1 in which said means for returning carriers along said return bar includes a conveyor movable along said return bar, an abutment on said conveyor engageable with each carrier moved to said return bar by said second transfer arm and operable to slide the carrier along said bar toward said first transfer arm, and means for driving said conveyor to feed successive carriers off said second transfer arm in response to the transfers of carriers to said return bar.

23. An automatic film processor as defined in claim 22 in which said conveyor is of the endless type having a run extending along said return bar to move said abutment along the return bar, from an out-of-the-way position spaced from the end of said return bar overlying said exit end, to the other end of the return bar, and including a reversible motor for driving said conveyor.

24. An automatic film processor as defined in claim 23 further including means responsive to the transfer of a carrier to said return bar to activate said motor and shift the carrier onto the return bar, and then to reverse the motor to move said abutment back to said out-of-the-way position.

25. An automatic film processor as defined in claim 24 further including means operable on demand to activate said motor to shift all carriers along said return bar until a carrier is fed off the return bar onto said first transfer arm, and then to reverse the motor to return said abutment back to said out-of-the-way position.

26. An automatic film processor as defined in claim 1 further including a third bar disposed between said track bar and said return bar and supported on said frame with its ends free and aligned with the ends of said return bar, a second series of tanks in a row along said third bar, second feed and traversing screws extending along said third bar, second operating means for shifting carriers between said angular positions on said third bar, and means for transferring carriers between said third bar and the other two bars, whereby the carriers are processed along two levels through two rows of tanks.

27. An automatic film processor as defined in claim 26 in which the axes of said transfer arms are equidistant from all three bars, whereby the arms are swingable into alignment with each bar to serve as said means for transferring carriers to and from said third bar.

28. An automatic film processor as defined in claim 1 in which at least one of said tanks has means partially covering the open upper end of the tank, said covering means defining a limited open area for admitting the film holders downwardly into the tank, a limited open area for removal of the holders from the tank, and a connecting open area for movement of the holders between said open areas during feeding of the carriers by said feed screw.

29. An automatic film processor as defined in claim 28 in which said covering means comprise insets attached to the upper end portion of said one tank.

30. An automatic film processor having, in combination:

a frame including spaced, upright end walls; a plurality of film carriers;

an elongated, substantially straight, track bar supported on said frame and defining a predetermined path for said carriers;

each of said carriers having a body movable along said bar and also rotatable relative thereto, an arm projecting outwardly from said body to move between film-raised and film-lowered positions during rotation of said body between first and second angular positions about said bar, and means on said arm for holding film to be processed;

a series of tanks supported on said frame between said end walls for treating film on one of said carriers when the arm thereof is in said film-lowered position;

an elongated feed screw extending along said bar and having feed sections engageable with a carrier thereon when the feed screw body of the carrier is in said first position, said feed screw acting, when engaged, to advance carriers along each of said feed sections at a preselected feed rate;

an elongated traversing screw extending along said bar and engageable with a carrier thereon when the body of the carrier is in said second position, said traversing screw acting, when engaged, to advance carriers along said bar at a preselected traversing rate;

means for rotating the body of each carrier on said bar back and forth between said first and second positions in accordance with a timed sequence, thereby alternately engaging said feed screw while disengaging said traversing screw for movement of a carrier at a feed rate in said film-lowered position, and then disengaging said feed screw while engaging said traversing screw for movement of said carrier at said traversing rate in said raised position;

and mechanism for delivering carriers one by one and upon demand to one end of said bar for processing of a film along the bar, removing each carrier adjacent the other end of the bar after such processing, and storing said carriers off the bar preparatory to re-use.

31. A film processor as defined in claim 30 in which said feed screw has a plurality of first screw sections thereon having screw threads of differing pitches to advance said carriers along the various sections at rates differing in accordance with said pitches.

32. A film processor as defined in claim 31 in which the screw threads of said sections are axially separated whereby said carrier is advanced along each section to the end thereof, and then dwells at the end until said body is rotated to said second position.

33. A film processor as defined in claim 32 in which said traversing screw has screw threads spanning the separations between said sections to become engaged as said body is rotated to said second position and thereby to traverse each carrier from the end of each first section to the beginning of the next first section.

34. A film processor as defined in claim 32 in which the screw threads of said traversing screw are axially separated second screw sections extending between the adjacent ends of adjacent first sections whereby said carrier is traversed across the separations in said first screw and then dwells at the end of a second section until said body is rotated to said first position.

35. A film processor as defined in claim 34 in which said rotating means comprise:

a coupling abutment on each carrier spaced radially from said bar and angularly movable between third and fourth positions as said body turns between said first and second positions;

an operator movable from a pick-up position to a traversing position and engageable with said abutments during such movement, when the abutments are at the ends of said first sections, to shift the same from said fourth position to said third position thereby to turn said body from said second position to said first position in order to raise said arm and engage the carrier with said traversing screw;

said operator acting upon movement back to said pick-up position to shift said abutments from said third position back to said fourth position when the abutments are at the end of said second sections;

and means for moving said operator back and forth between said pick-up position and said traversing position in accordance with said timed sequence.

36. A film processor as defined in claim 35 in which said operator comprises a plurality of axially spaced operating abutments axially alined with said second screw sections to span the separations between said first screw sections and remain in engagement with said coupling abutments during traversing of said carrier and during movement of one of said bodies from said second position to said first position, said operating abutments being supported for back and forth movement in unison between said pick-up and traversing positions.

37. A film processor as defined in claim 36 in which the coupling abutments are supported on said bodies to yield around said operating abutments as said operator moves to said pick-up position and to move the bodies to said second position and back to said first position as said operator moves from said pick-up position to said traversing position and back.

38. A film processor as defined in claim 36 in which said coupling abutments are surfaces on plungers slidably mounted on said bodies and spring-urged outwardly to extended positions, said plungers and said operator having coacting cam surfaces for shifting said plungers inwardly to permit the operator to pass the plungers to said pick-up position in order to engage said coupling abutments and move the latter from said fourth position to said third position.

39. A film processor as defined in claim 30 in which said mechanism includes a return bar spaced above and generally parallel to said track bar with ends generally overlying the ends of said track bar, and automatic transfer devices adjacent the ends of said bars for transferring carriers to said track bar upon demand and to said return bar upon completion of processing of a film along said path.

40. A film processor as defined in claim 39 in which said return bar is supported on said frame between its ends by means of an element engaging one side of the bar, said carrier bodies being generally horseshoe-shaped in cross-section so as to slide along said return bar and said supporting element.

41. A film processor as defined in claim 40 in which said track bar has a portion of reduced thickness at

each end for receiving said bodies, and said transfer devices include members movable vertically between said bars between positions on top of said reduced-thickness portions to positions alined with the ends of said return bar thereby to receive a carrier from one bar and deliver the carrier to the other bar.

42. A film processor as defined in claim 41 in which one of said screws has end sections for sliding carriers from one transfer device onto said track bar at one end and off the track bar to the other transfer device at the other end.

43. A film processor as defined in claim 41 in which said members are supported on arms having free end portions swingable about axes equidistant from corresponding ends of the bars thereby to swing each member back and forth between the bars.

44. A film processor as defined in claim 39 in which said mechanism includes a conveyor extending along said return bar and operable in response to delivery of carriers to the return bar from said track bar to shift the carriers onto the return bar and then slide the carriers along the return bar.

45. An automatic processor having, in combination:

25 a frame;

at least one carrier for holding an article to be processed;

means on said frame forming a plurality of upwardly opening treating compartments for said article, said compartments being arranged side by side in a row;

an elongated track supported on said frame to extend along said row, said carrier being movable along said track and also swingable relative thereto between raised and lowered positions, said carrier supporting said article within said compartments in said lowered position and above the compartments in said raised position;

first and second drive members extending along said track and alternately engageable with said carrier, said first member engaging said carrier in said lowered position to feed the article within a compartment, and said second member engaging said carrier in said raised position to traverse said carrier between compartments;

said first member having means thereon for moving said article through different compartments at different rates;

means responsive to the arrival of said carrier at the end of each compartment to shift the carrier to said raised position and into engagement with said second member;

and means responsive to movement of the carrier by said second member into alinement with each successive compartment to shift the carrier into said lowered position and into engagement with said first member.

46. An automatic film processor having, in combination:

60 a frame;

a plurality of carriers;

means forming an elongated, generally horizontal first slide track defining a path for said carriers and having entrance and exit ends;

means on said frame forming a plurality of treatment stations along said path;

means spaced vertically from said first track and forming an elongated second slide track defining a return path for said carriers from said exit and back to said entrance end; said carriers being slideable forwardly along said first track and reversely along said second slide track and being storable on said second slide track; first transfer means adjacent said entrance end for moving carriers one-by-one from said second slide track to said entrance end; second transfer means adjacent said exit end for moving said carriers one-by-one from said first slide track to said second slide track; loading means for placing film to be processed on said carriers adjacent said entrance end; means operable to move each carrier independently along said first slide track through a plurality of film processing stations in accordance with a prearranged sequence of motions thereby to process the film on each carrier; unloading means for removing processed film from said carriers adjacent said exit end; and means for moving said carriers reversely along said second slide track toward said entrance end preparatory to re-use.

47. An automatic processor for advancing a film strip through successive tanks containing processing liquids, said processor having, in combination:

- a frame;
- at least one carrier having means thereon for holding a film strip to be processed;
- means on said frame forming a track for movement of said carrier past said tanks and also supporting said carrier for rotation about said track between first and second angular positions, said holding means moving from a lowered position to a raised position as the carrier is rotated from said first position to said second position thereby to raise the film strip out of a tank;
- drive means for advancing said carrier along said track in said first angular position and traversing the carrier between successive tanks in said second angular position;
- and means for rotating the carrier in a timed sequence back and forth between said angular positions, said rotating means including an operator engageable with said carrier while the latter is

- in said first angular position and operable to rotate the carrier to said second angular position preparatory to traversing to another tank, and means controlling said operator during such rotation first to delay movement of the carrier momentarily through an intermediate position to allow time for draining of liquids, and then to snap the carrier into said second position to shake remaining liquid therefrom.
- 10 48. An automatic processor as defined in claim 47 in which said carrier is disengaged from said drive means in said intermediate position for draining of liquid into the tank from which the holding means have been raised, and is engaged with said drive means after being 15 snapped to said second position whereby liquid shaken from the holding means also falls back to the same tank.
49. An automatic processor as defined in claim 48 in which said drive means include separate drive members for advancing said carrier in said first and second angular positions, said drive members being disengaged while said carrier is between said positions.
- 20 50. An automatic processor as defined in claim 49 in which said operator is moved periodically back and forth through active and return strokes, said rotating means also including means for holding said operator at the ends of said strokes for preselected, timed intervals.
- 25 51. An automatic processor as defined in claim 50 in which said operator is an elongated bar movable back and forth through active and return strokes, in parallel with said track, by a reciprocating fluid actuator, and said control means include a valve variably regulating the fluid flow for said actuator in accordance with the position of said operator along said active stroke, 30 restricting said flow momentarily as said operator moves through said intermediate position for delayed motion, and releasing the restriction for the remainder of said active stroke to snap the carrier to said second position.
- 35 52. An automatic processor as defined in claim 51 in which said operator is formed with spaced abutments thereon engageable with said carrier after the latter has been driven to the end of each of said tanks by said drive means, said valve having a flow regulator moved by said operator during said active stroke to control said flow as an incident to movement of said operator.
